UNITED STATES PATENT OFFICE.

PERCY A. E. ARMSTRONG, OF LOUDONVILLE, NEW YORK, ASSIGNOR TO LUDLUM STEEL COMPANY, OF WATERVLIET, NEW YORK, A CORPORATION OF NEW JERSEY.

CARBURIZING BOX AND THE LIKE AND PROCESS OF MAKING SAME.

Application filed December 2, 1921. Serial No. 519,495.

To all whom it may concern:

Be it known that I, PERCY A. E. ARMSTRONG, a subject of the King of Great Britain, and a resident of Loudonville, county of Albany, and State of New York, have invented a new and useful Improvement in Carburizing Boxes and the like and Processes of Making Same, of which the following is a specification.

10 My invention relates to carburizing boxes and the like and the process of making same.

The invention is more particularly directed to the production of metal receptacles, such as carburizing boxes, annealing boxes 15 and the like which are subjected to use at high temperatures, as, for example, by being repeatedly subjected to high heat and to cooling.

It has been common to make carburizing 20 boxes of a one piece casting, but such boxes, particularly when made from alloy steel adapted to resist corrosion when heated, which is desirably to be used for this purpose, will sooner or later, even if apparently 25 found when first cast, develop cracks and breaks, particularly along the sides, due to the very severe strains set up in the cast material. The casting of such all-cast boxes presents numerous difficulties, and to secure 30 the necessary strength the boxes must be quite thick and heavy. These difficulties are avoided by the present invention and boxes produce, which can be put into use substantially immediately without extensive annealing, and which, while comparatively 35 light in weight, will stand up substantially indefinitely when subjected to heating and cooling, as in the case of carburizing and annealing boxes and the like, or to other 40 drastic treatment which would result in the destruction of the ordinary all-cast boxes or receptacles.

The invention is herein illustrated in certain of the views as embodied in boxes of 45 generally parallelopipedon form, such as customarily used for carburizing boxes, but the form of the boxes may be extensively varied, as will be readily understood.

In the construction of a box of this form 50 in accordance with the present invention, and comprising flat surfaces, the flat surfaces such as sides, ends and bottom are made up of previously formed plates or sheets, which may be of cast or rolled material or produced in any other suitable

manner. Such sheets or plates, which can be relatively light and thin, are placed adjacent to one another, but preferably not in contact, in a suitably formed mold and are joined together by cast metal, which in the 60 case of a rectangular box, may be poured within the mold to form the corners and bottom edges of the box, or if desired, one of the elements of the box, such as the bottom, may be formed integral with the cast 65 corners, the joining together of the side and end plates or sheets and their joining to the bottom being accomplished at the same time that the bottom is cast, and the boxes may be produced in still other ways. 70

For making the cast parts of the box material is preferably used which will weld to the sheets or plates with which it comes into contact. A good way of securing this result is to make the cast parts of the same material as the plates or sheets, and preferably both are made of "Silchrome," a stable surface alloy steel, as described in my Patent No. 1,322,511, of Nov. 25, 1919, and which is highly resistant to corrosion when heated. 80 While a weld is preferred for a fluid tight receptacle, it is not essential that a weld be formed in making receptacles such as carburizing boxes, and in such case the slight creeping which can take place between the 85 pre-formed plate or sheet members and the cast connecting members may be of advantage in reducing strains throughout the box.

In the accompanying drawings I have illustrated certain forms of carburizing 90 boxes in which my invention may be embodied, but it is to be understood that such showing is intended only for illustration and for affording an understanding of the invention and not for limitation thereof to 95 the forms shown. In said drawings, Fig. 1 is a plan view, with parts broken away, of a carburizing box and its cover, the box having the corner members for connecting the side wall plates or sheets cast integral 100 with the bottom. Fig. 2 is a longitudinal sectional view taken on the line 2—2, Fig. 1. Fig. 3 is a sectional view taken on the line 3—3, Fig. 1. Fig. 4 is a cross sectional view taken on the line 4—4, Fig. 3. Fig. 5 is a 105 horizontal sectional view of a molding apparatus set up to make the box of Fig. 1—4, and taken on the line 5—5, Fig. 6. Fig. 6 is a cross sectional view taken on the line 6—6, Fig. 5. Figs. 7 and 8 are re- 110

spectively cross-sectional and plan views of a box having a plate or sheet bottom connected at its edges to the plate or sheet sides and ends by cast metal, sectional Fig. 7 being taken on line 7—7, Fig. 8. Fig. 9 is a transverse sectional view of a substantially rectangular box having its corners welded before the cast corner members are formed thereon. Fig. 10 is a transverse sectional view of a box similar to that of Fig. 9, but having the side walls formed of a single sheet bent at three corners and having its edges welded at the fourth corner before the cast corner members are formed thereon. Fig. 11 is a perspective view of a round box having the side wall of a single plate, with one side wall joint. Fig. 12 is a transverse, cross-sectional view of a round box with the side walls made of two plates with two joints. Fig. 13 is a view similar to Fig. 11 of a ring shaped box adapted for ring gears and the like, the inner and outer side walls made of single plates with one joint in each. Fig. 14 is a transverse cross-sectional view of a box similar to that shown in Fig. 13, but having inner and outer walls made up of two plates respectively with two joints in each.

In the box of Figs. 1-4, reference character 10 is used to designate the box, and 11 the cover. The sides 12, 12 and ends 13, 13 are shown as plane sheets or cast plates suitably cut or otherwise brought to size and are assembled in the mold 14 (Figs. 5 and 6) with their edges adjacent to one another and fairly close together, but preferably out of contact with one another, the mold being so formed as to leave spaces 15, 15 for receiving the molten metal to form the corner members, 16, 16, into which the sides and end members 12, 12 and 13, 13 extend, as shown in Fig. 4. If desired, provision may be made for positively securing or keying the side and end plates to the corner members cast about the edges thereof. The term "plate" is here and hereafter used in the specification and in my claims to include sheets made by mechanical working, as by rolling, hammering and the like, as well as plates made by casting. The means for securing the cast metal and the plates together may be of various forms. In Fig. 4 I have shown holes 17 formed in the side and end plates, into which the molten metal may run, forming retaining keys 17'. In the box of Figs. 1-4, the bottom 18 is cast integral with the corner members 16, 16, the adjacent edges of the side and end plates extending into the spaces 19, 19 left in the mold for forming the thickened edge portions 20, 20 and the cast bottom 18, so that when the box is completed the side and end plates are secured to the bottom, as clearly shown in Fig. 2. Fastening means as shown in Fig. 4, for example, may be provided here, 65 if desired.

The construction of the box with the cast corners integral with the cast bottom is particularly well adapted for the construction of carburizing boxes of relatively small size, 70 but this type of construction may be used for larger boxes, if desired.

The bottom 18 preferably has short integral legs 21, 21 cast on its corners to support the box when in use. 75

The corner members 16, 16 are preferably rounded on the outside, as shown at 22, Fig. 1, and such outer portions 22 preferably extend flush with the top edges of side and end plates 12, 13. The inner parts 23 80 of the corner members 16 preferably extend inwardly to fill out the corner, as shown at 24, Figs. 1 and 4, and such inner parts 23 do not extend entirely to the top edges of the side and end plates, but are 85 notched out as shown at 25 (Figs. 2 and 3) to provide supports at each corner of the box for the inserted lid 11. Lid 11 preferably has an upwardly extending rib 26 about its upper surface, leaving a recessed 90 portion 27 between it and the upper edge of the box when the lid is in place in the box, said recessed portion 27 being adapted 95 to receive luting material, as clay or the like, to make a tight closure.

Lid 11 may be handled as by inserting a poker or the like instrument in the hole 28 formed in the cross lug 29 extending across the recessed portion 30. The tops of lug 29 and of rib 26 are preferably substantially flush with the upper edge of the box when the lid is in place, so that the boxes may be set one on top of another, if desired, as when placed in a carburizing 100 furnace. 105

The box of Figs. 7 and 8 differs from that of Figs. 1-4 by having the bottom made up of the pre-formed plate 31 connected to the side and end plates 12', 12' and 13', 13' by cast connecting members 31', 31' having legs formed integrally therewith. The vertical cast corner members 16', 16' may be cast integrally with the bottom edge members 31', 31', or may be cast separately 110 therefrom, as desired. In making the larger size carburizing boxes the bottom wall plate 31' preferably is a casting, and the side wall members 12' and 13' may also be made by casting, if desired, or these may be sheet metal plates. 115

The invention may be embodied in variously modified forms of boxes or pots. In Fig. 9 the sides 12" and ends 13" are welded together as indicated at 32, and further secured together by cast corners 33, 33. The welding may extend the full length of the meeting edges or only along a part or parts 120 of the meeting edges, as will be readily

125

understood and preferably an electric weld is used. In Fig. 10 all the sides are made of a sheet bent at the corners and its meeting edges welded at one corner as shown at 34, and the corners are reenforced by castings 35.

In Figs. 11-14 round boxes or pots are shown, the round box of Fig. 11 having its side walls 36 formed of a bent sheet, the edges whereof are brought together, with or without welding and the joint is enclosed in the cast member 37. Fig. 12 is like Fig. 11, except that two sheets are used, their edges being joined in the cast connecting members 38, 39. The boxes of Figs. 13 and 14 are like those of Figs. 11 and 12 respectively, except that they are annular in form and the inner ring shaped wall 40 may be made with a single joint enclosed in the cast connecting member 41, as shown in Fig. 13, or with a plurality of such joints, two such joints 43 and 44 being shown in Fig. 14.

It will be seen that a box constructed in accordance with my invention possesses numerous features of advantage, including among others, the following: A box so constructed is rigid and well adapted to stand hard usage, is virtually free from strains and, therefore, not subject to cracking or breakage upon heating and cooling, and is much lighter than an all-cast box, thus enabling the saving of valuable alloy material in manufacture, and securing economies in transportation and handling charges. With the thin walls of high thermal conductivity a considerable saving of time is effected, while largely avoiding heat losses heretofore involved in heating up much excess box material in carburizing and annealing furnaces and the like.

It is to be understood that modifications and changes may be resorted to within the scope of my claims, by which the invention is defined.

I claim:

1. A metal box for use at high temperatures made up of plates joined together by castings, said castings extending on both sides of the plates.

2. A metal vessel for use at high temperatures having wall portions of metal plate joined together by cast metal, the cast metal embracing and extending upon opposite sides of the wall portions.

3. A metal vessel for use at high temperatures having a joint in its walls, comprising wall portions of plate metal joined together by joining portions of cast metal integral to which the wall plates project, the cast metal extending upon both sides of the plate metal.

4. A metal vessel for use at high temperatures having wall portions of metal plates with the edges adjacent to one another, but

not in contact, and joined together by metal cast about the adjacent edges, and extending on both sides of the wall portions.

5. A metal box for use at high temperatures having walls composed of a plurality of metal plates with their edges adjacent to one another, and cast corner members connecting said plates.

6. A metal box for use at high temperatures having its side and end walls of metal plates, and the bottom of cast metal, the side wall plates being joined together by cast corner pieces integral with the cast bottom, the cast corner pieces extending on both sides of the wall plates.

7. A metal box for use at high temperatures having its side and end walls of metal plate, and its bottom wall of cast metal, the side wall plate extending into the bottom and the material of the bottom wall being cast about the bottom edges of the side and end walls.

8. A carburizing box comprising side walls of metal plate, and a bottom wall of cast metal cast around the lower edges of the side walls.

9. A carburizing box comprising side walls of metal plate, and corner members cast about the edges of the side walls and connecting the side walls, the corner members being adapted to support a cover at the corners of the box.

10. A metal box for use at high temperatures comprising plate side walls and cast corner members cast about the edges of the plate side walls and connecting the side walls, the interior parts of the cast corner members being of less height than the side walls, and a cover within the side walls and supported by its corners upon said interior parts of the corner members.

11. A carburizing box comprising side walls of metal plate, a cast bottom wall cast about and connecting the lower edges of the side walls, and cast corner members cast about and connecting the adjacent edges of the side wall plates, the corner members forming separated ledge members to support a lid within the box, and a lid supported on said ledge members and having an upwardly extending flange near its margin, forming a groove between the flange and the upper edges of the box for reception of luting material.

12. A carburizing box comprising a plurality of side wall members of metal plate, a cast bottom wall cast about the lower edges of the side walls, which are thereby embedded in the margin of the bottom wall, and the side wall members being joined at their corners by corner members of cast metal integral with the bottom wall, and cast about the adjacent edges of the side wall plates, which are thereby embedded in the corner members.

13. The process of making metal boxes for use at high temperatures, which comprises assembling metal plates with their edges adjacent to one another, and casting metal about such adjacent edges.
14. The process of making metal boxes for use at high temperatures, which comprises assembling metal plates with their edges adjacent to one another in a mold having an open space into which said edges project, leaving a space on each side of said edges and casting metal in said open mold space to extend on each side of the metal plates and connect said plates by their edges.
15. The process of making carburizing boxes, which comprises assembling side wall plates with their edges adjacent to one another, and casting a bottom wall and cast corner members integral with the bottom wall about the bottom edges of the plates and their adjacent edges respectively.

In testimony that I claim the foregoing, I have signed my name hereto.

PERCY A. E. ARMSTRONG.
